No. 851,531.

PATENTED APR. 23, 1907.

J. LEA.

STAIR.

APPLICATION FILED JUNE 19, 1906.

UNITED STATES PATENT OFFICE.

JOSEPH LEA, OF TORONTO, ONTARIO, CANADA.

STAIR.

No. 851,531.

Specification of Letters Patent.

Patented April 23, 1907.

Application filed June 19, 1906. Serial No. 322,477.

To all whom it may concern:

Be it known that I, JOSEPH LEA, of the city of Toronto, in the county of York, in the Province of Ontario, Canada, have invented certain new and useful Improvements in Stairs, of which the following is the specification.

My invention relates to improvements in stairs, and the object of the invention is to devise a simple, cheap and durable form of stairs, which may be erected as the building proceeds and before completion, may be used without temporary treads, and which may be adapted to all buildings without material change of patterns, and the difficulty and the delay incident thereto.

Further objects are to make such a stairs as may be quickly erected, capable of being applied to any design of stairs, which will expand and contract with greater safety than a stair as at present built and will sustain a greater load for a given weight of material.

The invention consists of an interlocking 25 riser and tread, the interlocking portion being located on the longitudinal edge of both riser and tread, which fit one within the other being in the form of a hollow bead, and a stringer of steel or other suitable material into or through which extend bolts, which pass through the stringer and thereby support the interlocked riser and tread together. The treads may have hollow beaded edges through which the stringers the 35 bolts extend in order to support the treads in position between the stringers.

The parts are otherwise constructed and arranged in detail as hereinafter more particularly explained.

Figure 1 is a view of a portion of a stair constructed in accordance with my invention. Fig. 2, is a longitudinal section through Fig. 1. Fig. 3, is an enlarged detail showing the interlocking of the riser and tread. Fig. 4, is a view of a modification.

In the drawings like letters of reference indicate corresponding parts in each figure.

A are the stringers, which may be made of any suitable material preferably channel 50 steel. The outside of the stringers may be ornamental, if desired, in any suitable manner.

B are the risers and C are the treads, which are preferably also made of plate

steel. Each riser B is provided at the edge 55 with a hollow bead B' and at the bottom with a hollow bead B². The bead B' is turned outwardly and the bead B² inwardly. The tread is provided with a hollow nosing C' at the front, which is adapted to fit closely over the hollow bead B' at the top of the tread, and a hollow molding C² at the top, which is adapted to fit over the bead B² at the bottom of the next riser. It will thus be seen that the risers and tread are interlocked.

D is a bolt, which extends from stringer to stringer through the bead B', and the bolt being provided with washers E outside both stringers and nuts E' fitting on to the 70 threaded ends of the bolt and abutting the washers. D' is a similar bolt extending through the hollow bead B² and similarly secured at the outside by washers and nuts E² and E³ respectively as indicated. It 75 will now be seen that not only are the treads and risers held securely in position, but also the stringers are held securely to the treads so as to make a rigid and strong structure.

Although I preferably use the bolts extending through the beads as hereinbefore described, it will be understood that lugs, projections or short bolts might extend into the beads and be secured therein, so as to hold the risers and treads together as well as 85 the stringers to them without departing from the spirit of my invention.

I preferably provide supplemental treads F, where the stair is to be used in good buildings. Such supplemental stair, of course, 90 may be made of marble, slate, wood or any other suitable material.

In Fig. 4, I show treads C³ having the bead nosing C⁴ and back edge C⁵. Through the nosing and back edge extend bolts E⁴, which are provided with suitable nuts and washers at the outside of the stringer. By such a construction I am enabled to make an open 95 stairway at but a minimum expense.

Such a construction of stair as I describe 100 will give a maximum strength for a minimum weight of material used, and it is simple in construction. The simplicity of adjustment of rise and go to suit all conditions render unnecessary the usual cost and 105 delay of changing patterns for stringers and brackets to suit various heights of floors in a building.

No temporary treads are required as the stair is erected with the permanent tread, thus allowing the use of the stair as the building proceeds.

5. The stair is necessarily a light one and all use of heavy cast iron is avoided.

In case of fire also the stair being a compact structure would expand and contract with greater safety than stairs built in the usual way held together by ordinary bolts and rivets.

It will also be understood from what has been heretofore described, that a stair constructed in accordance with my invention 15 will sustain a greater load for a given weight of material. Such a stair may be made of steel or any other suitable material.

What I claim as my invention is:

1. In a stair, the combination with the 20 stringers of treads having a hollow beaded nosing, and means extending into the hollow nosing for maintaining the treads in position and securing the stringers together and to the treads as and for the purpose specified.

25. 2. In a stair, the combination with a stringer, of treads having a hollow beaded nosing, and means extending into the hollow nosing for maintaining the treads in position and securing the stringers together, consisting of a bolt extending through the stringers and nosing as and for the purpose specified.

3. In a stair, the combination with the 35 stringers, of treads extending between the same and having hollow curled or beaded nosings and backs, and means extending from the stringers into the nosing and backs for supporting them upon the stringers and connecting the stringers together as and for the purpose specified.

40. 4. In a stair, the combination with the stringers, of treads extending between the same and having hollow curled or beaded nosings and backs, and bolts extending

through the hollow nosings and backs and connecting the stringers and treads together 45 as and for the purpose specified.

5. In a stair, the combination with the stringers, of the treads having a hollow nosing and a curled or upwardly extending back edge and the risers having a hollow forwardly turned bead fitting within the nosing and a hollow rearwardly turned bead fitting within the curled back, and means extending into the hollow beads at the top and bottom for connecting the stringers and risers and 55 treads together as and for the purpose specified.

6. In a stair, the combination with the stringers, of the treads having a hollow nosing and a curled or upwardly extending back 60 edge, and the risers having a hollow forwardly turned bead fitting within the nosing and a hollow rearwardly turned bead fitting within the curled back, and bolts extending through the hollow top and bottom beads of 65 the riser, and fastening nuts or devices located in the outer ends of the bolts as and for the purpose specified.

7. In a stair, the combination with the stringers, of the treads having a hollow nosing 70 and a curled or upwardly extending back edge and the risers having a hollow forwardly turned bead fitting within the nosing and a hollow rearwardly turned bead fitting within the curled back, and a supplemental 75 tread suitably fastened to the tread as and for the purpose specified.

8. In a stair, the combination with the stringers, of the treads, and bolts connected to the treads and extending longitudinally in 80 alinement therewith through the stringers as and for the purpose specified.

JOSEPH LEA.
